VARIABLE RESISTOR

Shunzo Oka, Hirakata, and Akitoshi Miyashita, Suita, Japan, assignors to Matsushita Electric Industrial Co., Ltd., Osaka, Japan

Filed July 2, 1971, Ser. No. 159,585

Term of patent 14 years

Int. Cl. D13—03

U.S. Cl. D26—1 D

FIG. 1

FIG. 2

FIG. 3

FIG. 1 is a top, rear perspective view of a variable resistor showing our new design;

FIG. 2 is a front, perspective view thereof, from the opposite side to that of FIG. 1, with the mounting plate oriented vertically; and

FIG. 3 is a left, side elevational view thereof as positioned in FIG. 2.

We claim:

The ornamental design for a variable resistor, as shown and described.
